(57) **CLAIM**

The ornamental design for an interphone master unit, as shown and described.

DESCRIPTION

FIG. 1 is front view of an interphone master unit illustrating my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a front perspective view thereof.

The broken lines shown in the drawings represent portions of the interphone master unit that form no part of the claimed design.
